J. W. TOMPSON,
HOLDER FOR SHARPENING RAZOR BLADES.
APPLICATION FILED MAY 6, 1920.

Patented Oct. 26, 1920.

1,356,799.

Inventor
John W. Tompson

UNITED STATES PATENT OFFICE.

JOHN W. TOMPSON, OF OKLAHOMA, OKLAHOMA.

HOLDER FOR SHARPENING RAZOR-BLADES.

1,356,799.

Specification of Letters Patent. Patented Oct. 26, 1920.

Application filed May 6, 1920. Serial No. 379,388.

To all whom it may concern:

Be it known that I, JOHN W. TOMPSON, a citizen of the United States, and a resident of Oklahoma city, in the county of Oklahoma and State of Oklahoma, have invented certain Improvements in Holders for Sharpening Razor-Blades, of which the following is a specification, reference being had to the accompanying drawings.

10 The object of the invention is to provide a cheap, simple, and convenient holder for sharpening razor blades.

Figure 1 of the drawings is a perspective view showing the improved holder and a 15 fragment of a strop on which it is being used.

Fig. 2 is a perspective view showing the two main portions of the holder in position for assemblage.

Fig. 3 is a plan view of the blade-holding 20 end of the holder.

Fig. 4 is an enlarged sectional view taken on the line 4—4 of Fig. 3, also showing two double-edge blades which do not appear in Fig. 3.

25 Fig. 5 is a reproduction of Fig. 4, but showing single-edge blades.

Like characters of reference designate like parts in all the figures.

In carrying out the object stated, the improved holder comprises two elongated and similarly shaped portions 6 and 7 which meet each other on a plane and are adapted to contact in gripping and holding the blades to be sharpened.

35 The blade-holding end of each of the portions 6 and 7 is widened as shown, so that two blades 8 of the width commonly used may be clamped between them at the same time.

40 To provide an alining guide for placing the blades 8 in the holder, an elongated stud 9 is mounted on the holding face 10 of one of the portions, 6, and the holding face 10 of the other portion 7 is recessed, as at 11, to 45 freely clear said stud.

The distance between the stud 9 and the edges 13 of the gripping portions 6 and 7 is such that the blades 8, when placed with their inner edges in contact with said stud, 50 project out far enough to have their outer edges honed on the strop 14.

In order not to dull the blades 8, the stud 9 is of leather, rubber, or some other material that will not affect a cutting edge.

The recess 15 in which the stud 9 is set is 55 under-cut to yieldably hold said stud in place.

Many of the single-edge blades 16 used are narrower than the double-edge blades 8 and have a ribbed or thickened rear edge 17.

60 The gripping faces 10 of the portions 6 and 7 are therefore recessed, as at 19, to freely clear the thickened rear edges 17 of the blades 16; and in alining these blades 16 said rear edges 17 abut the rear edges 20 of the recesses as shown in Fig. 5.

65 At the opposite end 21 the meeting face of the portion 6 is provided with a dowel stud 22, and this stud fits in a recess 23 on the face of the other portion 7.

70 A screw 24 holds the two portions 6 and 7 in assemblage and in forced gripping contact with the blades, and said screw and the stud 22 hold said portions in proper alinement with each other.

75 The following is claimed:—

1. In a device of the class described, two clamping portions meeting each other on a plane, one of the portions having a stud of yieldable material to guide and aline the 80 edges of blades inserted between the two portions, the other portion having a recess to clear said stud.

2. In a device of the class described, two clamping portions meeting each other on a 85 plane, releasable means for holding the two portions in assemblage, one of the portions having a stud of yieldable material to guide and aline the edges of blades inserted between the two portions, the other portion having a recess to clear said stud.

3. In a device of the class described, two clamping portions adapted to have the edges of blades inserted between them, the clamping faces of the portions being recessed to 95 clear the thickened edges of ribbed blades, the edges of the recessed faces being adapted to form a guide for the purpose of properly alining said thickened edges.

4. In a device of the class described, two 100 clamp-portions meeting each other on a plane and adapted to have the edges of razor

blades inserted between them, releasable means for holding the portions together and in forced gripping contact with the blades, one of the portions having on its clamping 5 face an elongated yieldable stud for alining the edges of the inserted blades, the other portion having a recess to receive said stud,

both of the portions also being recessed adjacent said stud to receive and aline the edges of ribbed blades.

Witness my hand this 3rd day of May, 1920.

JOHN W. TOMPSON.
